(57) **CLAIM**

The ornamental design for a parallelogram design element for a digital photo frame as shown and described.

DESCRIPTION

FIG. 1 is perspective top view of the parallelogram design element for a digital photo frame.

FIG. 2 is a zoomed in view of the invention depicted in FIG. 1.

FIG. 3 is a left side view of the parallelogram design element for a digital photo frame; and,

FIG. 4 illustrates a left side view and a top view of the parallelogram design element for a digital photo frame.

The broken lines illustrated in FIGS. 1-4 depicting portions of a picture frame are included for the purpose of illustrating environmental structure and forms and are not part of the claimed design.

1 Claim, 3 Drawing Sheets

FIG. 1

FIG. 2

FIG. 3

FIG. 4
